FOOD DISPLAY RACK

Richard D. James and Samuel Groupe, Chicago, Ill.,
assignors to Universal Metal Products Company, Chicago, Ill., a corporation of Illinois

Application August 22, 1956, Serial No. 42,703

Term of patent 7 years

(Cl. D80—11)

The single figure of the drawing is a perspective view as seen from the front of the food display rack.

As seen from the rear, the food display rack differs from the front view of the drawing only in that the base portion comprises a plain cylinder.

We claim:

The ornamental design for a food display rack, as shown and described.
